Edward F. Bouhall, Cleveland, Ohio, assignor to
The C. L. Gouger Keyless Lock Company, Kent,
Ohio

Application October 8, 1945, Serial No. 122,630

Term of patent 14 years

(Cl. D50—8)

To all whom it may concern:

Be it known that I, Edward F. Bouhall, a citizen of the United States, residing at Cleveland, in the county of Cuyahoga and State of Ohio, have invented a new, original, and ornamental Design for Combination Keyless and Key Lock, of which the following is a specification, reference being had to the accompanying drawing, forming part thereof, wherein:

Figure 1 is a perspective view of a combination keyless and key lock showing my new design.

Figure 2 is a rear elevational view of the same.

Figure 3 is a side elevational view of the same.

I claim:

The ornamental design for a combination keyless and key lock, substantially as shown.

EDWARD F. BOUHALL.
